ATTORNEYS.

UNITED STATES PATENT OFFICE.

SVEN A. ALLAN STENBERG, OF SAN FRANCISCO, CALIFORNIA, ASSIGNOR OF FORTY-NINE ONE-HUNDREDTHS TO WILLIAM E. CUMBACK, OF SAN FRANCISCO, CALIFORNIA.

FIRE APPARATUS.

SPECIFICATION forming part of Letters Patent No. 795,176, dated July 18, 1905.

Application filed May 26, 1903. Serial No. 158,830.

To all whom it may concern:

Be it known that I, SVEN A. ALLAN STENBERG, a subject of the King of Sweden and Norway, and a resident of San Francisco, in the county of San Francisco and State of California, have invented a new and Improved Fire Apparatus, of which the following is a full, clear, and exact description.

The invention relates to stationary fire systems; and its object is to provide a new and improved fire apparatus designed for use on fire-hydrants in streets and other places and arranged to permit firemen, policemen, watchmen, and other authorized persons to make immediate use of the apparatus for extinguishing fires in the immediate neighborhood in which the hydrant is located.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a front elevation of the improvement, showing the casing-door open. Fig. 2 is a transverse section of the same on the line 2 2 of Fig. 1. Fig. 3 is a rear elevation of the same, the casing and other parts being broken out. Fig. 4 is a plan view of the same. Fig. 5 is a perspective view of the pump-frame. Fig. 6 is an enlarged sectional side elevation of the pump and the hose and nozzle connections, the section being on the line 6 6 of Fig. 7. Fig. 7 is a sectional plan view of the same on the line 7 7 of Fig. 6. Fig. 8 is an enlarged front elevation of the switch-board. Fig. 9 is an enlarged sectional rear elevation of the drain-cock in the stand-pipe; and Fig. 10 is a similar view of the same, showing the plug in a draining position.

The frame A of the fire-hydrant is set on a suitable foundation on a street or other place, and the stand-pipe B of the hydrant connects in the usual manner with the street-main or other suitable source of water-supply. The

stand-pipe B is provided with one or more branch pipes B', extending through the sides 50 of the frame A, and the outer end of each branch pipe is provided with a coupling member to allow of attaching a hose to the branch pipe for street washing, sprinkling, and other purposes, the said branch pipes B' being normally closed, however, by suitable screw-caps B², as shown.

On the top of the frame A is secured a casing C, having a door C' normally locked by a suitable locking device C², the key to which 60 is in the possession of an authorized person, such as a fireman, policeman, watchman, or the like.

In the lower portion of the casing C is arranged a motor D of any approved construction, preferably, however, an electric motor, as shown, the said motor serving to actuate a pump, preferably a duplex pump, and for this purpose the shaft D' of the motor D is provided with a pinion E (see Fig. 1) in mesh 70 on opposite sides with crank gear-wheels E', connected by pitmen E² with cross-heads E³, connected with the pistons or cylinders E⁴ of the duplex pump, mounted on a frame E', secured to the inside of the casing C, as plainly 75 shown in the drawings. The suction ends of the cylinders E⁴ of the duplex pump are connected by branch pipes B³ with the upper end of the stand-pipe B, and the discharge-pipe F of the duplex pump is provided with forks 80 F', connecting with the under side or bottom G' of a dome G, attached to the top of the casing C, and on the sides of this dome G are arranged branch pipes G², adapted to be coupled with a fire-hose and nozzle H, as shown 85 in Fig. 1, the said branch pipes G² being normally closed, however, by screw-caps G³, as indicated in Fig. 6. The dome G is provided on the top with an outlet G⁴, adapted to be closed by a gate-valve I, having a screw-stem 90 I' extending to the outside of the dome and provided with a squared end I², to be turned by the operator to move the gate-valve I into an open or closed position, the said gate-valve I when open connecting the dome G by way 95 of the outlet G⁴ with the tubular base J' of

a nozzle or water-tower device J of any approved construction.

The stand-pipe B below the branch pipes B³ and above the branch pipes B' is provided 5 with a drain-cock B⁴ (see Figs. 9 and 10) for connecting or disconnecting the stand-pipe with the branch pipes B³ or for connecting the branch pipes B³ with a drain-pipe B⁵, leading from one side of the cock, as indicated in the said drawings. The drain-cock B⁴ is under the control of the operator by the use of a handle or hand-wheel B⁶ on the stem of the cock B⁴, it being understood that when the cock B⁴ is in the position shown in Fig. 15 9 connection is had between the stand-pipe B and the branch pipes B³, and when the cock is turned to the position shown in Fig. 10 then the stand-pipe B is closed to the branch pipes B³, and the latter are connected with 20 the drain-pipe B⁵ to drain the pump and connected parts thereof. Now when the cock B⁴ is in an open position, as shown in Fig. 9, the stand-pipe B is connected with the pump-cylinders B⁴, and in case of a fire an authorized 25 person opens the casing C and starts the motor D, so that the pump is actuated and pumps the water by the pipes F and F' into the dome G, from which the water can be taken by the hose and nozzle H to extinguish 30 the fire or by way of the nozzle or tower device J on the operator opening the valve I.

As shown in the drawings, the nozzle device J is provided with a hollow fork J², mounted to turn on the tubular base J', and in the said 35 fork J² are journaled the trunnions J³ of the nozzle J⁴ to allow of swinging the latter up and down. On one of the trunnions J³ is secured a disk J⁵, on which is fulcrumed a handle J⁶, normally pressed on by a spring J⁷ to hold 40 the handle in engagement with registering shoulders held on the base J⁸ and the fork J², so that the nozzle J⁴ is locked against turning. When it is desired to swing the nozzle up or down, the operator swings the handle 45 J⁶ outward against the tension of the spring J⁷ to unlock the nozzle and to allow the operator to swing the same up or down for the nozzle to direct the stream of water onto the fire. By swinging the handle J⁶ out of engagement 50 with the registering shoulders the fork J² becomes unlocked from the base J', and hence the fork and nozzle can be turned on the base as a vertical axis, and in order to facilitate this turning the base J⁸ of the nozzle 55 is provided with handles J⁹, as indicated in the drawings.

Feed-wires K for the electric motor D connect with the main-line conductors L, leading to a distant supply-station, and the said feed-wires K connect with a rheostat N, supported on the frame E⁵ of the duplex pump, the rheostat being provided with a suitable switch-lever N' for gradually starting the motor and for stopping the same whenever desired. The 65 feed-wires K are connected by heating-wires

K² with a switchboard O of any approved construction and mounted on the frame E⁵, and from the said switchboard lead wires K³, formed into a coil K⁴, wound around the discharge-pipe F of the duplex pump, so as to 70 heat the water passing from the pump to prevent freezing thereof in cold weather.

If desired, the dome G may be provided with a pressure-chamber G⁵, as indicated in Fig. 6. The pressure-chamber when employed is preferably mounted in the dome G in order to take up but little space and add to the compactness of the apparatus. The lower end of the pressure-chamber extends through the central opening in the removable plate G', forming the bottom of the dome, and a screw-threaded connecting-joint holds the pressure-chamber in place and also unites the pressure-chamber with the pipe connection which branches off to the pumps. This pipe connection is shown broken in the lower part of Fig. 6, the connections with the pumps not being shown.

From the foregoing it will be seen that the fire apparatus as shown and described forms 90 a permanent fixture of the water-hydrant, and the fire apparatus can be readily set in motion by an authorized person, so as to force a stream or streams of water by suitable hose and nozzles to the fire to extinguish the same 95 in a comparatively short time. Thus from the foregoing it will be seen that on the discovery of a fire it is not necessary for the watchman, fireman, or policeman to await the arrival of a fire apparatus from a distant station, 100 but the fire apparatus on the hydrant can be immediately set in action to pump streams of water, and hence no valuable time is lost.

I do not limit myself to the particular construction of the motor and pump shown and 105 described, as the same may be varied without deviating from the spirit of my invention.

Having thus described my invention, I claim as new and desire to secure by Letters Patent—

1. A fire apparatus, comprising a fire-hydrant having a stand-pipe connected with the water-main, a pump mounted on the hydrant, a motor for actuating the pump, the stand-pipe leading to the suction of the pump, a dome connected with the discharge of the 110 pump and having coupling members for engagement by coupling members of the fire-hose, and a drain-cock in the said stand-pipe for closing the latter to the water-main and for draining the water from the pump, as set 115 forth.

2. A fire apparatus comprising a fire-hydrant, having a stand-pipe connected with the water-main, a casing fixed on the said hydrant, an electric motor in the said casing, a 125 pump in the casing, driven by the said motor, the said pipe connection leading to the suction of the pump, and a dome mounted on the said casing and having its inlet connected with the discharge or outlet of the pump, the 130

dome having coupling members for engagement by coupling members of the fire-hose, as set forth.

3. A fire apparatus comprising a fire-hydrant, having a stand-pipe connected with the water-main, a casing fixed on the said hydrant, an electric motor in the said casing, a pump in the casing, driven by the said motor, the said pipe connection leading to the suction of the pump, a dome mounted on the said casing and having its inlet connected with the discharge or outlet of the pump, the dome having coupling members for engagement by coupling members of the fire-hose, and a nozzle supported on the dome and mounted to swing up and down and to turn on a vertical axis, as set forth.
4. A fire apparatus comprising a fire-hydrant, having a stand-pipe connected with the water-main, a casing fixed on the said hydrant, an electric motor in the said casing, a pump in the casing, driven by the said motor, the said pipe connection leading to the suction of the pump, a dome mounted on the said casing and having its inlet connected with the discharge or outlet of the pump, the dome having coupling members for engagement by coupling members of the fire-hose, a nozzle supported on the dome and mounted to swing up and down and to turn on a vertical axis, and a switch for the electric motor, to start or stop the same, as set forth.
5. A fire apparatus comprising a fire-hydrant, having a stand-pipe connected with the water-main, a casing fixed on the said hydrant, an electric motor in the said casing, a pump in the casing, driven by the said motor, the said pipe connection leading to the suction of the pump, a dome mounted on the said

casing and having its inlet connected with the discharge or outlet of the pump, the dome having coupling members for engagement by coupling members of the fire-hose, a nozzle supported on the dome and mounted to swing up and down and to turn on a vertical axis, and a manually-controlled valve on the said dome, for connecting and disconnecting the dome and the nozzle, as set forth.

6. A fire apparatus comprising a hydrant, having a stand-pipe connected with a water-main, a casing fixed on the said hydrant and into which projects the stand-pipe, an electric motor mounted in the said casing, a pump adapted to be driven by the said motor and having its suction connected with the said stand-pipe, the pump having an outlet for connection with hose and nozzle feeders for the said electric motor, and a heating-current connected with the feeders and passing around the said outlet, as set forth.

7. A fire apparatus comprising a fire-hydrant having a stand-pipe connected with the water-main, a casing fixed on the said fire-hydrant and containing a motor and a pump actuated thereby, the said stand-pipe leading to the suction of the pump, a nozzle connected with the discharge of the pump, and a drain-cock in the said stand-pipe, for closing the latter to the street-main and for draining the water from the pump, as set forth.

In testimony whereof I have signed my name to this specification in the presence of two subscribing witnesses.
